UNITED STATES PATENT OFFICE

EDWARD KENNETH SANDEMAN, OF ALDWYCH, LONDON, ENGLAND, ASSIGNOR TO
INTERNATIONAL STANDARD ELECTRIC CORPORATION, OF NEW YORK, N. Y.

DISTRIBUTOR FOR USE IN TELEGRAPHY OR THE LIKE

Application filed February 10, 1931, Serial No. 514,761, and in Great Britain February 12, 1930.

This invention relates to means for distributing the use of a communication channel, in turn to a number of telegraph transmitters and receivers.

5 The object of the invention is to provide a means or method for enabling a large number of telegraph instruments to operate over a connecting channel, and which does not necessarily require the employment of high 10 speed mechanical moving parts.

According to one feature the invention comprises a plurality of energy translating devices, for instance vacuum tubes, arranged in groups. The number of translating devices in any intermediate group lies intermediate the number of such devices in the adjacent groups and means are provided for disabling or blocking the translating devices in such a way that at any particular instant 20 only a predetermined number of translating devices in each group is permitted to be operative as energy translators and the selection of such operative translators is obtained automatically by electrical or mechanical effects impressed upon said translating devices.

25 The following description has reference particularly to an embodiment employing several valves arranged in a pyramid form so that a multiplicity of signal or code indications influencing their input circuits may be distributed in time to a common circuit; or at the receiving end a plurality of code indications may be sorted out by a similar arrangement, to operate the required and corresponding receiving instrument or printer.

30 Other features of the invention will be apparent from the following description in which:—

35 Fig. 1 illustrates schematically a distributor arranged and operating according to the principles of the present invention.

Fig. 2 is a curve illustrating the manner in which the grid bias on the tubes of Fig. 1 45 may be modified to give intermittent blocking of the valves.

Fig. 3 illustrates schematically a modified embodiment of a distributor according to the present invention.

50 Fig. 4 illustrates schematically a still fur-

ther modification of the present invention, and

Fig. 5 is a diagram used to illustrate a condition of the valves which may occur in the arrangement of Fig. 3.

55

In Fig. 1 is shown a schematic arrangement for a transmitter terminal in accordance with this invention. The part above the chain dotted line consists of eight graphical portrayals of biasing or paralyzing voltage waves applied to the grids of certain valves in the lower part of the figure. The lower part of the figure contains a valve pyramid fulfilling the function of a distributor, that is connecting a number of sending devices in turn to the same circuit.

A, B, C, D and E are respectively groups of two, four, eight and sixteen and one thermionic valve numbered serially in each row. The valves are coupled together so as to form 70 an amplifier with one output and sixteen inputs, corresponding to the sixteen grid circuits of valves D₁ to D₁₆. Valve E may conveniently be a detector valve, and the other valves are ordinary amplifiers when in an 75 operating condition. Valves D₁ and D₂ have their output coupled in parallel to the input of valve C₁, valves D₃ and D₄ have their outputs in parallel coupled to the input of C₂. Valves C₁ and C₂ have their outputs in parallel 80 coupled to the input B₁. The whole of the pyramid is built up in a similar manner. α₁ is a paralyzing square wave of frequency a equal to the number of letters per second 85 per instrument.

85

$$= \frac{WL}{60} = 4$$

β₁, γ₁ and δ₁ are square waves of frequency respectively 2a, 4a, and 8a used for paralyzing purposes as described below. α₂, β₂, γ₂, and δ₂ are square waves of frequency respectively equal to α₁, β₁, γ₁ and δ₁, but in opposite phase also used for paralyzing purposes.

The paralyzing wave α₁ is applied to the 95 grids of valves D₁, D₃, D₅, D₇, D₉, D₁₁, D₁₃, D₁₅, and the paralyzing wave α₂ is applied to the grids of the valves D₂, D₄, D₆, D₈, D₁₀, D₁₂, D₁₄, D₁₆. To the grids of C₁, C₃, C₅ and C₇ are applied a paralyzing wave β₁ whilst 100

to the other valves of the group C a paralyzing wave β_2 is applied. Similarly waves γ_1 and γ_2 are applied to alternate valves in group B whilst valve A_1 has applied to it a paralyzing wave δ_1 and valve A_2 as a paralyzing wave δ_2 . It will be seen that the valves near the apex of the pyramid are applied with paralyzing waves of high frequency and those near the base of the pyramid with paralyzing waves 10 of low frequencies. The paralyzing wave δ_1 is applied to the grid of valve A_1 in such a way that during positive half cycles of δ_1 valve A_1 is in an operating condition and during negative half cycles of δ_1 valve A_1 is 15 in a nonoperating condition. Fig. 2 shows the way in which biasing potentials are applied to A_1 . The axis I_b is plate current and V_g is grid voltage. E_n is the biasing potential required for optimum performance of the 20 valve as an amplifier. E_p is the biasing potential required to make the valve completely inoperative for signals of the new magnitude applied to the grid at any time.

$$Ec = \frac{1}{2}(E_p + E_n)$$

25 is the value of steady bias applied to the valve. $Y = \frac{1}{2}(E_p - E_n)$ is the amplitude of the paralyzing wave. Since the paralyzing waves are all square waves it follows that any 30 valve to which a paralyzing wave is applied in the above manner is rendered completely inoperative and completely operative during alternate equal and contiguous time intervals.

The lines on Fig. 1 running from the axis 35 of each wave (α_1, β_1 etc. α_2, β_2 etc.) are intended to indicate the point on the valve pyramid at which this wave is applied. The circuit by which it is applied will be described later. For clearness in description the axis 40 T of time along which the waves are shown has been divided into sixteen time intervals each equal in duration to half a period of the waves δ_1 and δ_2 . During a time equal to the sum of these sixteen time intervals one complete cycle of events occurs: each transmitter 45 sets up one new letter from each transmitter sent over the line L .

50 Consider the interval numbered (1). During this interval wave δ_1 is positive and δ_2 is negative so that valve A_1 is operative and valve A_2 is inoperative, so that all currents coming from relay tongues 2, 10, 6, 14, 4, 12, 8, 16 are blocked.

55 Also wave γ_1 is positive and wave γ_2 is negative so that valve B_1 is operative and valve B_2 is inoperative thus nullifying any currents originating in relay tongues 3, 11, 7, 15.

60 Similarly valve C_1 is operative and C_2 inoperative so that currents from relay tongues 5 and 13 are blocked.

65 Finally the paralyzing of valve D_2 by α_2 blocks current from relay tongue 9, leaving only a path for currents originating from generator C via relay tongue 1 if operated by

relay 1. This path proceeds by valves D_1, C_1, B_1, A_1 and E.

Similarly it may be shown that in interval 2, a path is open for currents from relay tongue 9 only; in interval 3 from relay tongue 5 only and so on, the relay tongues becoming operative in the order 1, 9, 5, 13, 3, 11, 7, 15, 2, 10, 6, 14, 4, 12, 8, 16.

It therefore follows that the valve pyramid of Fig. 1 fulfils the function of a distributor 75 effectively connecting each relay in turn to the line. In order to lay emphasis on the rapidity with which this operation may be carried out it will be referred to as scanning and the relay which at any moment is effectively connected to the line will be referred to as the scanning point.

Returning to Fig. 1, P_1, P_2 and P_3 are three printing telegraph transmitters of known type which operate by setting up different 85 combinations of the relays $R_1, R_2, R_3, R_4, R_5, R_6$, etc. Each of the relays has two positions corresponding to a marking position and a spacing position. In the marking position the tongue (T_1, T_2 etc.) is held down on the corresponding contact to the common bus bar KK which is energized by AC a source of high frequency current which may be referred to as the carrier frequency. The frequency of this source is not critical provided it lies well above the frequency range which the telegraph is required to fill. For example, if it were required to occupy a range of 90 500 cycles suitable values for the carrier frequency would be 1,000 cycles to 10,000 cycles 100 and it would be possible to exceed this limit in either direction provided the amplifiers following are capable of handling the side-band products of modulation formed by the switching on and off of the carrier frequency 105 by the relay tongues T_1, T_2 etc.

By means of a rotating device, indicated symbolically by W in Fig. 1, the three printing telegraph transmitters P_1, P_2 and P_3 are caused to operate in turn, each setting up a 110 letter on its five associated R relays during time T_s and leaving it set up during time T_1 , after which the process is repeated with the next letter. In general the value of T_s will be much smaller than the value of T_1 . 115

Though not essential to the method, the commencements of each of the three intervals T_{s1}, T_{s2}, T_{s3} , corresponding respectively to the printers P_1, P_2 and P_3 , most conveniently may be separated from one another by equal time intervals if the time taken to set up any relays S is omitted. (These relays 120 S represent spare relays, occurring because the valve pyramid requires a number of relays equal to a power of two, while the printing telegraphs require a number of relays equal to a multiple of five). The same is true 125 of the commencements of each of the intervals T_{11}, T_{12} , and T_{13} which mark the terminations of intervals T_{s1}, T_{s2} and T_{s3} . It is 130

convenient to associate the cycle of events with a rotating vector V_t which may be identified with a particular line along a radius of the rotating device (i. e. the device actuating the printer), the angular position of which determines which transmitter is actuated, i. e. caused to move its transmitting tape one letter forward and so break down one combination of its five relays and set up the next combination. The position of the scanning point may conveniently be associated with a rotating vector V_s . It is evident that the vectors V_t and V_s must on the average rotate at the same rate, small fluctuations in rate being permissible provided the V_t never passes V_s or vice versa; this last proviso is obviously necessary since scanning of a relay and change of relay setting must evidently not take place at the same time. This will be considered in detail later. Each vector makes one revolution in time

$$T_s + T_1 = T_{s1} + T_{s2} = T_{s2} + T_{12} = T_{s3} + T_{13}.$$

Vector V_s progresses in a series of sixteen jumps per period with no time interval between, remaining in each position for a time $\frac{1}{16}(T_s + T_1)$. Vector V_t on the other hand is considered to rotate uniformly.

Since the waves α_1, β_1 etc. α_2, β_2 etc. can all be derived from one or more sets of current generated by an alternator on the axis of W , the relative positions of V_t and V_s can evidently be maintained with extreme precision at the transmitting end.

A practical difficulty occurs in generating waves which are exactly square in form and it is probable in practice that the beginnings and the ends of the time intervals during which a valve is intended to be maintained at constant voltage, the valve grid biasing voltage will tend to move towards the value corresponding to the axis of zero voltage of the wave. In other words, a rounding off of the corners of the waves will occur. In the case of the wave of highest frequency, this will probably not be serious because it will simply mean that the transmitted signal will approximate to the form in which it is received, (i. e. the effect will be similar to suppression of the high frequency components of the square wave). In the case of the waves which are not the waves of highest frequency, as long as the period of rounding is considerably smaller than half the full period of the waves of highest frequency the rounding will probably not be serious, but as soon as this rounding approximates in duration to half the period of the wave of highest frequency it means that the operation of the valves to which this wave is applied will be indeterminate during the period of the rounding. That is, during the period over which the rounding takes place the valve will not be fully operated or fully paralyzed as the case may be. It is therefore desirable to

devise some system which will operate satisfactorily with waves which are not square waves. The most convenient type of wave to use is evidently a sine wave since this is most easily generated, though the scope of the invention is not limited to the use of sine waves. Fig. 3 shows a system of waves fulfilling a function identical with that carried out by the system of waves shown on Fig. 1. In this case it has been assumed, as suggested above, that the rounding of the so-called square waves is negligible for waves γ_1 and γ_2 and δ_1 and δ_2 , and these waves are therefore kept unaltered and the part of the valve pyramid to which they are applied remains unaltered, as does also their manner of application. The following replacements of waves α_1 and α_2 and β_1 and β_2 has however been made.

Wave α_1 is replaced by waves αa and αb

Wave α_2 is replaced by waves αc and αd

Wave β_1 is replaced by waves βa and βb

Wave β_2 is replaced by waves βc and βd

For simplicity in explanation the waves α_1 and α_2 and β_1 and β_2 are shown dotted along the same axes as the waves $\alpha a, \alpha b, \alpha c$, and αd and $\beta a, \beta b, \beta c, \beta d$.

βa is a sine wave of the same frequency as β_1 and of such phase with regard to it that it reaches its maximum in either direction $\frac{1}{8}$ of a period after the square wave β_1 has changed polarity.

βb lags 90° on wave βa so that it reaches a maximum at a point $\frac{1}{8}$ of a period before wave β_1 changes polarity.

Referring to Fig. 2 it was seen that amplitude Y of the square wave is given by $\frac{1}{2}(E_p - E_n)$. E_p is the voltage required to paralyze the valve and E_n is the voltage required to bias the valve to its operative condition. It is evident that providing the amplitude of the signals transmitted is made considerably less than E_n , as can easily be done, E_n is not critical in value. This means that the value of $\frac{1}{2}(E_p - E_n) = Y$ is not a critical figure. It follows that if it be insured that the peak amplitude of wave βa always lies above the value required to paralyze the valve a suitable choice of conditions can easily be made such that the valve will operate satisfactorily for any value of the paralyzing wave lying between say $+M$ and $+N$. Similarly, since any value or negative voltage greater than a certain amount will secure paralysis of the valve, it follows that conditions can be arranged such that complete paralysis occurs effectively with the value of negative voltage of $-N$ and, of course, the valve remains paralyzed when this voltage varies anywhere between $-N$ and $-M$.

It follows therefore that, any valve having the wave βa applied to it is definitely operative in intervals 1, 2, 9 and 10 and is completely paralyze in intervals 5, 6, 13 and

14. During periods 3, 4, 7, 8, 11, 12, 14 and 16 the condition of the valve can best be regarded as indeterminate. From the above explanation it is immediately obvious what is the condition of any valve in any interval when supplied with a given wave.

It will be noticed that valves A_1 and A_2 have waves of completely opposite phase. This is also true for valves B_1 and B_2 and 10 also for valves B_3 and B_4 and for valves C_1 and C_2 and so on. It follows therefore that when any valve of one of such a pair is operative the other valve of the pair is inoperative. It follows at once that if a path is 15 open from any one of the D valves to the apex, no other path can be open, e. g. In Figure 5 is shown the condition of affairs in interval 1. The solid circle represents a valve completely blocked, the half solid circle represents in an intermediate condition and the other circle represents a valve entirely operative. The order of opening of the paths is identical with that occurring in the arrangement of Figure 1 and an identical 20 system of cross connection between relays and valves must be employed.

Figure 4 employs a system of waves identical with that shown in Fig. 3 and applies them to a different arrangement of valves. 25 The manner in which the waves are applied is however analogous. In the pyramid of valves, valve A_1 in said figure has been replaced by two valves A_1 and A_2 , valve A_2 in said figure has been replaced by two valves 30 A_3 and A_4 . A similar doubling of the number of valves has been done in row B. The remaining valves remain the same. Considering the combinations of valves A_1 and A_2 , it is evident that A_1 is operative during time 35 intervals 1, 2, 3 and 4 and A_2 is operative during time intervals 5, 6, 7 and 8. It follows 40 therefore that a path is available through the combination A_1 and A_2 during the time intervals 1-8 that is, during exactly the same 45 intervals as the path was available when the square wave was applied. Similar comments 50 may be applied to every group. It is therefore evident that paths will be available in the manner identical in every way with the 55 manner in which paths become available in the former arrangement. An analysis of each time interval along the lines of Figure 60 5 shows also that a number of indeterminate paths exist. That is to say, paths which are 65 traced from the base of the pyramid to the apex of the valve and which contain no valve completely paralyzed but one or more valves whose condition has previously been regarded 70 as indeterminate. This condition of affairs can be changed by adjusting the amplitudes 75 of the paralyzing waves. For instance, it would probably be possible to secure satisfactory operation by adjusting the paralyzing wave so that during the indeterminate period for a particular valve the amplifica-

tion of the valve is always appreciably less than during the period at which it is supposed to be operating. An alternative method, of course, would be by the supplying of two paralyzing waves of the same magnitude 70 to the same valve, differing in frequency.

What is claimed is:

1. An arrangement for use in a telegraph system employing a distributor comprising several valves adapted to operate as a multiple switching arrangement, a means for providing a substantially square wave, said means comprising an amplifier valve, and a voltage operated device comprising a neon lamp shunted by a condenser associated with 80 the output circuits of said amplifier valve.

2. A distributor for telegraph or the like comprising valves arranged in a plurality of groups, circuits adapted to join and interconnect the numbers of valves of the groups in a convergent series, and means adapted to feed paralyzing waves to said valves to render them periodically operative, inoperative, or in an intermediate state so that at any particular moment only a predetermined number (usually one) of conductive paths through the valves in the largest group to the valves in the smallest group are established.

3. A distributor according to claim 2 95 wherein all the valves of at least one group are arranged in pairs there being means adapted to impress one valve of a pair with a paralyzing wave of the same frequency but different phase from the paralyzing wave 100 impressed on the other valve of the said pair (preferably 180° phase difference), the paralyzing waves of any pair differing in phase (preferably by 90°) from the corresponding wave of an adjacent pair in the 105 group.

4. An arrangement for use in a telegraph system or the like comprising groups of valves, circuits adapted to join and interconnect the numbers of valves of the groups in a convergent series, and means adapted to feed paralyzing waves to the valves in different groups, a valve of the group with the largest number of valves having paralyzing 110 waves of the lowest frequency and the valves 115 of the other groups having paralyzing waves whose frequencies are graded accordingly.

5. A distributor for telegraph or the like comprising groups of valves, circuits adapted to join and interconnect the numbers of valves of the groups in a convergent series, means for applying different paralyzing waves to the valves in different groups wherein paralyzing potentials on at least one of the groups of valves are in the form of a 120 plurality of waves adapted to simulate the 125 effect of a single square wave.

6. A distributor for telegraph or the like comprising valves arranged in a plurality of groups, circuits adapted to join and intercon-

nect the numbers of valves of the groups in a convergent series, and means for applying paralyzing waves to the valves in different groups wherein paralyzing potentials on 5 at least one of the groups of valves are in the form of a plurality of waves displaced in phase so as to simulate the effect of a single square wave.

7. A distributor for telegraph or the like 10 comprising valves arranged in a plurality of groups, circuits adapted to join and inter-connect the numbers of valves of the groups in a convergent series, and means for applying paralyzing waves to the valves in differ- 15 ent groups wherein valves to which are applied paralyzing waves of other than square form are arranged in pairs or multiples corresponding to the number of waves replacing the square waves, each pair or multiple hav- 20 ing common input and common output cir- cuits.

In witness whereof I hereunto subscribe my name this twenty sixth day of January 1931.

25 EDWARD K. SANDEMAN.
